[57] CLAIM

The ornamental design for a pump for bottle of spring water, as shown and described.

DESCRIPTION

FIG. 1 is a perspective view of the pump for bottle of spring water;

FIG. 2 is a front plan view thereof;

FIG. 3 is a left side view thereof;

FIG. 4 is a right side view thereof;

FIG. 5 is a top plan view thereof;

FIG. 6 is a bottom plan view thereof; and,

FIG. 7 is a front plan view in practical use thereof, and shown at a reduced scale.

The broken line showing of a container is for illustrative purposes only and forms no part of the claimed design.
